UNITED STATES PATENT OFFICE.

RALPH B. MACNISH, OF ST. LOUIS, MISSOURI.

CIRCUIT-BREAKER.

1,139,789.

Specification of Letters Patent. Patented May 18, 1915.

Application filed May 1, 1911, Serial No. 624,440. Renewed April 10, 1915. Serial No. 20,548.

To all whom it may concern:

Be it known that I, RALPH B. MACNISH, a citizen of the United States, residing at the city of St. Louis, in the State of Missouri, have invented certain new and useful Improvements in Circuit-Breakers, of which the following is a specification.

In the past the principal use of electric current on automobiles has been for engine ignition, the most satisfactory source of current being the alternating-current magneto. It is desirable, however, to apply electricity to various other uses upon the car, as, for instance, for lighting purposes, but since the use of electric light renders the provision of a battery practically necessary, a current generator should be employed which is adapted to charge a battery. This an alternating-current magneto cannot do without complications which would be prohibitive upon an automobile, and therefore the use of electric light upon automobiles necessitates the provision of a direct-current generator.

It is the object of this invention to obviate the necessity for employing separate generators for ignition current and lighting current, eliminating the alternating-current magneto and providing means whereby the current supplied by the battery may be applied to the ignition devices in such a way as to retain all the advantages of magneto ignition systems. The means alluded to comprises a governor-controlled timer or circuit-breaker adapted automatically to maintain the closed-circuit period of the induction coil or coils constant, notwithstanding changes in the speed of the engine, or to cause the closed-circuit period to vary in any desired manner, as the engine speed changes.

The invention contemplates such a construction of the timer as to adapt it to maintain the closed-circuit period of the induction coil constant, notwithstanding the speed range of the engine is considerable. At present, automobile engine speeds practically always vary as much as six to one, ratios as high as ten to one being not at all uncommon, and the tendency is toward still greater flexibility. The timer of my in-

vention is adapted to compensate for such great speed ranges, and not merely such slight ranges as two to one or three to one.

A further object is to provide speed-controlled means for automatically advancing or retarding the spark.

In the accompanying drawings, Figure 1 is an end view of a governor-controlled circuit-breaker illustrating one embodiment of the invention. Fig. 2 is a side elevation of said circuit-breaker. Fig. 3 is a sectional view taken in the plane of dotted line 3-3 of Fig. 1. Fig. 4 is a section on line 4-4 of Fig. 2. Fig. 5 is a development of the cam construction of the circuit-breaker. Fig. 6 is a sectional view of one form of spring which may be used in the governor.

For the purpose of describing the invention it may be considered in connection with a single-spark ignition system for a multiple-cylinder engine, the system comprising a circuit-breaker operated by the engine, a single induction coil, and a distributor. It will be understood, however, that the invention is not limited to use in single-spark systems, nor to use with multiple-cylinder engines, and that it may be employed in connection with individual induction coils controlled by a timer.

The circuit-breaker 4 is arranged to maintain the closed-circuit period of the induction coil constant, despite variations in engine speed, or to cause the closed-circuit period to vary in any desired degree. A single-spark circuit-breaker for use with any constant-voltage source of current supply, such as a storage battery, must be provided with means for keeping the closed-circuit period of the coil approximately constant if the circuit-breaker is to be used to the best advantage on engines whose speed varies within wide limits, as is the case with automobile engines. Where a magneto is used, the conditions are altogether different. The primary current from the magneto is in the form of a wave, the circuit-breaker being adjusted ordinarily to close the circuit at a certain point in the wave, and to break the circuit at such point in the wave as will produce a spark of the required intensity. The magneto circuit-breaker ordi-

5 narily closes for a certain invariable fraction of a turn of the armature so as to keep in step with the number of degrees comprised in the usable part of the current wave. While such a circuit-breaker as is used on magnetos can be made to work with a battery current, the best results cannot be expected on any engine whose speed varies to any large amount. If the circuit-breaker 10 is so made that the closed-circuit period is right for the lowest engine speed, there will be a gradually weakening spark as the engine speed increases. If the circuit-breaker is so made that the closed-circuit period is 15 right for the maximum engine speed, there will be a great waste of current at the lowest speed without any increase in the size of the spark, since the current that flows through the coil after it is saturated is wasted in ohmic resistance. The quicker 20 break as the speed increases tends to strengthen the spark, but this strengthening effect does not neutralize the weakening effect of the shortening of the closed-circuit period. To remedy this difficulty I provide 25 means whereby the length of the arc of contact at the circuit-breaker is increased directly or in any desired ratio as the speed increases, whereby the closed-circuit period 30 remains constant, or changes in any desired ratio, and whereby, with constant pressure like that from a storage battery, the spark or flame is of the same or any desired intensity at all speeds. This means comprises 35 a governor, preferably centrifugal, arranged to act upon one of the circuit-breaker elements, as, for example, the cam, so that the number of degrees of rotation between the closing and the opening of the contacts will 40 vary directly or in any desired ratio with the speed.

In the present embodiment, the circuit-breaker comprises a depression cam and a spring-pressed lever 14 carrying a shoe or 45 roller 15 adapted to drop into the depression to close the primary circuit of the induction coil. Said depression is made automatically adjustable in length so as to lengthen the arc of contact between the roller 15 and the 50 depression as the speed of the engine is increased, in order to compensate for the shortened period of contact between the points 16 and 17 of the circuit-breaker. If desired, said depression may also be arranged 55 to shift bodily to advance and retard the timing of the opening of the contacts. Various forms of cams may be used to obtain these results, the construction herein illustrated being as follows: A sleeve 18 60 is rotatably mounted on the armature shaft or other engine-driven shaft 6 so that it may be angularly adjusted about the shaft. Rotatably mounted upon said sleeve 18 is a sleeve 19 having an opening 20 therein 65 of sufficient breadth to receive the roller 15,

and a narrower opening 21 connected with the opening 20 and incapable of receiving the roller 15. On the inner sleeve 18 is a boss 22 of a height to lie flush with the periphery of the outer sleeve and extending 70 through the openings in the outer sleeve. The opening 21 is of such a size that the boss 22 may lie entirely therein. It will be seen that if the inner sleeve 18 be rotated with relation to the outer sleeve so that the boss 75 22 is moved toward and away from the edge 23 of the opening 20, the effective size of said opening will be varied, since the roller 15 cannot drop into the opening 20 until said roller has passed the edge 24 of the boss 22. 80

The means for rotating the sleeves 18 and 19 comprises, in the present illustrative embodiment, a spider 25 fixed to the shaft 6, two weighted governor arms 26 27 pivoted at diametrically opposite points on the 85 spider 25, two oppositely extending arms 28 fixed to the sleeve 18, two oppositely extending arms 29 fast on the sleeve 19, a pin 30 attached to each arm 28 and extending through a slot 31 in each governor arm, a pin 32 fixed to each arm 29 and extending through a slot 33 in each governor arm, and spring means acting on the governor arms to restrain pivotal movement of said arms due to centrifugal action. This spring 90 means may be of any suitable character, preferably one providing a differential action. Herein is shown a relatively heavy compression spring 34 bearing at one end against the end wall of a casing 35, and a 100 light compression spring 36 separated from the heavier spring by a slidable collar 37, one end of the spring 36 bearing against the end of a draw-rod 38, the other end of said rod being pivoted to the governor arm 27, 105 and one end of the casing being pivotally attached to the governor arm 26.

It will be seen that when the shaft 6 is rotated, the cam sleeves 18 19 are caused to revolve with the shaft by reason of the connection between said sleeves and the governor arms, the latter in turn being connected to the shaft. As the engine speed increases, the governor arms swing outwardly and thereby act upon the pins 30 to cause the 115 inner sleeve 18 to turn with reference to the shaft, (such turning movement being clockwise in Fig. 4). The boss 22 is thus moved in the direction away from the edge 23 of the opening 20, whereby the effective length 120 of said opening is augmented to compensate for the higher engine speed, and thereby maintain constant the closed-circuit period of the induction coil. The outward movement of the governor arms also causes the 125 outer sleeve 19 to turn (clockwise in Fig. 4) with reference to the shaft 6, whereby the time of the opening of the contacts 16 17 is advanced, and the sparks thereby advanced with relation to the position of the pistons. 130

The angular advance of the coil loading-time sleeve 18 is much greater for a given swinging movement of the governor arms than is the angular advance of the spark-advance sleeve 19; therefore to compensate for the sudden action of the governor at starting (when the light spring 36 alone resists the weights), the slots 33 in the governor arms are so formed that they advance the spark-advance sleeve more rapidly for the first few degrees of swing of the governor arms than for the remainder of the movement of said arms.

In the drawings I have illustrated a circuit-breaker causing one break per revolution. In constructing a timer for controlling individual induction coils, the sleeves 18 and 19 would, of course, be provided with sets of openings and bosses, the sets corresponding to the desired number of breaks per revolution.

Single-spark ignition systems as heretofore constructed, have included, as the source of electrical energy, dry cells or storage batteries intended to be charged at a charging station. For this reason such systems have necessarily been arranged to consume the smallest amount of current which would provide a fairly good spark. A floating-battery system is adapted to provide as strong a spark as the magneto system, or even a much stronger spark. Since the battery is maintained in a charged condition by a generator of suitable current output, and since the governor-controlled timer prevents waste of current, coils utilizing current much in excess of those commonly employed may be used. For example, a coil with multiple windings may be safely used, so that a heavy inductive effect may be obtained in even the very short loading time available in high-speed engines.

It will be understood that the circuit-breaker herein disclosed is suitable for use with stationary, marine or any other internal-combustion engines having a considerable speed range.

It will be noted that I employ only one circuit-breaker, and that by suitably controlling said circuit-breaker I am able to maintain the closed-circuit period of the induction coil constant, notwithstanding the fact that the range of speed of the engine is considerable.

In the following claims I have used the term "circuit-breaker" as a generic term to include breakers and timers providing one or several breaks per revolution. I have also used the term "active portion" to designate a depression or projection by means of which the lever is actuated to open and close the circuit.

I claim as my invention:

1. In an ignition system, a circuit-breaker comprising a lever and a cam, a circuit-clos-

ing contact on one end of said lever, a member coacting with said cam mounted on said lever intermediate its ends, said cam having a depression on its surface, means for varying the length of said depression, said circuit being closed when said member coacts with said depression.

2. In an ignition system, a circuit-breaker, a rod carrying said breaker, said breaker comprising members rotatable with reference to said rod and having a common axis therewith, said members forming a depression cam, a member adapted to co-act with said cam, the cam-forming members on the one hand, and the coacting member on the other hand being rotatable with reference to each other, and speed-controlled means for varying the length of the depression in said cam, while maintaining constant the distance of said cam from the axis of said rod.

3. In an ignition system, a circuit-breaker comprising a lever and a cam, a shaft for rotating one of said circuit-breaker parts with reference to the other, said cam comprising a plurality of members rotatable on the axis of the shaft with reference to each other and coacting to form an active portion of variable length, and speed-controlled means for thus rotating said cam-members with reference to each other.

4. In an ignition system, a circuit-breaker, a shaft for actuating said breaker, said breaker comprising members rotatable with the shaft and having a common axis therewith, said members forming a depression cam, and speed-controlled means for varying the length of the depression in said cam, while maintaining constant the distance thereof from the axis of said shaft.

5. In an ignition system, a circuit-breaker, a shaft for actuating said breaker, the latter comprising means rotatable with the shaft and forming a depression cam, and speed-controlled means for varying the length of depression of said cam and for shifting the depression circumferentially of the shaft, while maintaining constant the distance of said depression from the axis of said shaft.

6. In an ignition system, means for determining the length of the closed-circuit period of an induction coil, comprising two elements one of which is a rotary depression cam of varying size and the other a bar with an electric contact-point on one end, said bar being arranged to be acted upon by said cam, and means for shifting said elements with relation to each other to bring different portions of said cam into operative relation with said bar, while maintaining constant the distance thereof from the center of rotation of said cam.

7. In an ignition system, a circuit-breaker, a shaft for actuating said breaker, the latter comprising means rotatable with the

- shaft and forming a depression cam; and speed-controlled means for varying the length of the depression of said cam, while maintaining constant the distance thereof from the center of said shaft.
8. In an ignition system, a circuit-breaker, a shaft for actuating said breaker, the latter comprising means rotatable with the shaft and forming a depression cam; and speed-controlled means for shifting the depression circumferentially of the shaft, while maintaining constant the distance of said depression from the center of said shaft.
9. In an ignition system, a circuit-breaker comprising two members having a common axis, one of said members being apertured, and the other member having a portion extending into the aperture; the circuit-breaker also comprising an element adapted to enter said aperture; means for rotating said members; and means for shifting one of the members with relation to the other to vary the position of said portion within the aperture.
10. In an ignition system, a circuit-breaker comprising two members having a common axis, one of said members being apertured, and the other member having a portion extending into the aperture; the circuit-breaker also comprising an element adapted to enter said aperture; means for rotating said members; and speed-controlled means for shifting one of the members with relation to the other to vary the position of said portion within the aperture.
11. In an ignition system, a circuit-breaker comprising two members having a common axis, one of said members being apertured, and the other member having a portion extending into the aperture; the circuit-breaker also comprising an element adapted to enter said aperture; a rotary shaft on which said members are mounted; and means for shifting both of said members with relation to the shaft.
12. In an ignition system, a circuit-breaker comprising two telescoping sleeves; a rotary shaft on which said sleeves are mounted, the outer sleeve being apertured and the inner sleeve having a portion extending into said aperture; the circuit-breaker also comprising an element adapted to enter said aperture; and means for differentially rotating said sleeves with relation to the shaft.
13. In an ignition system, a circuit-breaker comprising two telescoping sleeves, a shaft on which said sleeves are mounted, the outer sleeve being apertured and the inner sleeve having a portion extending into said aperture, the circuit-breaker also comprising an element adapted to enter said aperture, a member attached to said shaft, a governor arm pivoted on said member, means tending to restrain centrifugal movement of said arm, and a connection between said arm and the inner sleeve for shifting said sleeve with relation to the outer sleeve.
14. In an ignition system, a circuit-breaker comprising two telescoping sleeves, a shaft on which said sleeves are mounted, the outer sleeve being apertured and the inner sleeve having a portion extending into said aperture, the circuit-breaker also comprising an element adapted to enter said aperture, a member attached to said shaft, a governor arm pivoted on said member, means tending to restrain centrifugal movement of said arm, and a connection between said arm and each of said sleeves for differentially turning said sleeves with relation to the shaft.
15. In an ignition system, a circuit-breaker comprising two telescoping sleeves, a shaft on which said sleeves are mounted, the outer sleeve being apertured and the inner sleeve having a portion extending into said aperture, the circuit-breaker also comprising an element adapted to enter said aperture, a member attached to said shaft, two governor arms pivoted at diametrically opposite points on said member, means tending to restrain centrifugal movement of said arms, and connections between said arms and said sleeves for causing the latter to turn in the swinging movement of said arms.
16. In an ignition system, a circuit-breaker comprising two telescoping sleeves, a shaft on which said sleeves are mounted, the outer sleeve having two communicating apertures of different widths and the inner sleeve having a projection adapted to lie within the narrower aperture, the circuit-breaker also comprising an element adapted to enter the wider aperture and incapable of entering the narrower aperture, and means for turning the inner sleeve to move said projection into and out of the wider aperture.
17. In an ignition system, a circuit-breaker, a shaft for actuating said breaker, said breaker comprising means rotatable with the shaft and forming a depression cam, and speed-controlled means independent of said rotatable means for varying the length of the depression in said cam.
18. In an ignition system, a circuit-breaker, a rod carrying said breaker, said breaker comprising means rotatable with reference to said rod and forming a depression cam, a member adapted to co-act with said cam, said cam-forming means and coacting member being rotatable relatively to each other, and speed-controlled means for varying the length of the depression of said cam, and for shifting the depression circumferentially of the shaft, while maintaining constant the distance of said cam from the axis of said rod.

19. In an ignition system, a circuit-breaker comprising a cam and a coacting circuit-controlling member, means for causing relative rotation between said cam and said member on an axis passing through the cam, said cam consisting of a plurality of members providing a depression between them, and means for rotating said cam-forming members with relation to each other on the

axis aforesaid to vary the length of said depression.

In testimony whereof I hereunto affix my signature in the presence of two witnesses.

RALPH B. MACNISH.
